UNITED STATES PATENT OFFICE.

OLIVER L. DARWIN, OF MILWAUKEE, WISCONSIN.

WAVE AND TIDE MOTOR.

Application filed May 31, 1927. Serial No. 195,438.

This invention relates to wave and tide motors.

Objects of this invention are to provide a novel form of wave and tide motor which 5 may be placed in the surf and which is automatic in its action and so constructed that reciprocal motion of a float is transformed into rotary motion in such a manner that each direction of travel of the float 10 imparts rotary motion to the rotary member, and to provide means for equalizing the intermittent or unequal rate at which the energy is supplied by the wave motor, so that the unit transmits continuous rotary 15 motion which may be used in any suitable manner.

Further objects are to provide a very simple type of wave motor which has few parts and in which the parts are of rugged 20 and reliable construction and not likely to get out of order.

Further objects are to provide a wave motor having the above characteristics, which is compact and consequently does not 25 present a large surface to the wind or other disturbing elements, but which nevertheless functions in a regular and reliable manner and is capable of picking up a large amount of power.

30 An embodiment of the invention is shown in the accompanying drawings in which:

Figure 1 is an elevation of the device;

Figure 2 is a sectional view on the line 2—2 of Figure 1;

35 Figure 3 is a detail of one of the ratchet devices.

Referring to the drawings, it will be seen that the wave motor comprises a series of uprights 1 which are carried by a suitable 40 base 2 and which carry the working mechanism. The uprights are braced by suitable cross members, as shown in the drawing, to secure the requisite strength. They form a substantially rectangular frame relatively 45 high and of comparatively small lateral dimensions.

The lower portion of the frame carries a grooved pulley 3 which is revolvably mounted upon a fixed shaft 4. This pulley is provided with a triangular framework constituting a projecting arm 5 which carries a float 6 at its outer end. The float is of sufficient size and also of the proper weight to operate the apparatus, as will hereinafter 55 appear. The arm 5 has spaced feet which are secured by bolts 7 to the wheel or pulley 3

at widely spaced points to thus secure the requisite strength and stability.

The upper portion of the apparatus carries a transverse shaft 8 which is provided with a pair of pulleys 9 preferably smaller than the pulley 3, although obviously these proportions may vary. These pulleys 9 are loosely mounted upon the shaft 8 and are adapted to be thrown into connection therewith by means of pawls 10 carried by the pulleys 9 cooperating with ratchet wheels 11 rigid with the shaft 8. A cable 12 is passed over the pulleys 9 and around the pulley 3, and its downwardly extending ends are held 70 taut by means of the weights 13. Thus, when the float 6 rises and falls, due either to tides or waves, the pulley 3 is rocked first one way and then the other and, consequently drives the cable or belt 13. This motion is 75 transformed into rotary motion at the pulleys 9, the pulleys 9 rotating in opposite directions. The ratchet mechanism is such that the shaft 8 is rotated in the same direction, irrespective of the direction of rocking or rotation of the pulley 3, as is apparent from 80 a consideration of Figures 1 and 3. It is to be noted particularly from Figure 1 that the ratchets 10 extend in opposite directions so that while one ratchet slides past the teeth 85 the other ratchet operatively engages the teeth. Thus, the shaft 8 is intermittently driven in the same direction by the oscillatory motion of the float 6.

A second shaft 14 is journaled on the upper 90 portion of the frame 1. The shafts 8 and 14 are each provided with spur wheels or sprocket wheels 15 and 16, respectively. A chain 17, preferably of the silent chain type, is formed in a continuous loop, as shown in 95 Figure 2, and passes over the sprocket wheels 15 and 16. It also passes over a flat faced roller 18 attached to a heavy weight 19. The downwardly looped portion passing beneath the roller 18 is positioned between the sprocket wheels 15 and 16, and the free 100 stretch of the chain hangs downwardly, as shown in dot and dash lines in Figure 2. Preferably, the shaft 14 is provided with a power takeoff pulley 20 to further insure 105 uniform rotary motion of such shaft.

In operation, the float 6 is raised and lowered intermittently and, consequently, intermittently rotates the shaft 8, thus winding up the weight supporting loop of the 110 chain. The weight in descending, rotates the shaft 14 and the flywheel 20 in a con-

tinuous and uniform manner, and irrespective of the intermittent supply of energy furnished by the float, the shaft 14 is driven at a continuous and uniform rate.

5 It is apparent that power may be taken from the shaft 14 in any desired manner and that this power will be delivered at a uniform rate.

It will be seen that a novel form of wave 10 and tide motor has been provided by this invention which is of extreme simplicity and which is so constructed that the weight acts as an equalizer to store up energy in a portion of the unit itself before this energy is 15 passed on in a uniform manner to the driving shaft or power shaft 14. The jack shaft 8 is intermittently rotated, as stated, but this obviously produces no effect upon the continuous rotation of the shaft 14, as the 20 weight 19 stores up any energy in excess of that demanded at the shaft 14 at any given instant.

It will be seen also that the device is extremely compact in comparison to the 25 amount of energy that it is capable of absorbing from the waves and tides.

Although the invention has been described in considerable detail, such description is intended as illustrative rather than limiting 30 as the invention may be variously embodied and as the scope of such invention is to be determined as claimed.

While I have shown the power takeoff pulley 20 having a belt connection, obviously 35 I may, without departing from the spirit of the invention, employ any suitable gear wheel or gear train in connection with the shaft 14, whereby the slow moving shaft will speed up the driving connection, the ratio of the speed- 40 ing up being arbitrarily arranged as the case may warrant.

I claim :

1. A wave and tide motor comprising a 45 unitary structure consisting of a frame, a pulley pivotally mounted upon said frame and having an outwardly projecting arm, a float carried by said outwardly projecting arm, a jack shaft having a pair of pulleys loosely mounted thereon, ratchet mechanism 50 for automatically connecting said last mentioned pulleys to said jack shaft when they are rotated in a predetermined direction, a cable passing over said first mentioned pulley and said last mentioned pair of pulleys, 55 means for holding said cable taut, a power delivering shaft mounted adjacent said jack shaft and carried by said frame, a continuous flexible member passing over said jack shaft and said power delivering shaft and having 60 a downwardly looped portion, a roller carried within the downwardly looped portion of said chain, and a weight for urging said roller downwardly to thereby equalize the

energy intermittently supplied by said jack shaft and transmitting said energy to said power delivering shaft in a continuous and uniform manner.

2. A wave and tide motor comprising a 70 unitary structure consisting of a frame, a pulley pivotally mounted upon said frame and having an outwardly projecting arm, a float carried by the outer end of said arm and adapted to rock said pulley first in one direction and then in the other, a jack shaft carried by the upper portion of said frame 75 and having a pair of pulleys loosely mounted thereon, a cable passing over said pair of pulleys and around said first mentioned pulley and having downwardly extending free ends, weights carried by said free ends for holding said cable taut, ratchet mechanism for connecting said pair of pulleys to said jack shaft for intermittently rotating said jack shaft in a predetermined direction, a sprocket wheel carried by said jack shaft, a power delivering shaft mounted adjacent 80 said jack shaft, an endless chain passing over said sprocket wheels and having a downwardly looped portion between such sprocket wheels, a roller fitted within the downwardly looped portion of said chain, and a heavy weight carried by said roller and urging said looped portion downwardly.

3. A wave and tide motor comprising a 85 unitary structure consisting of a frame, a pulley pivotally mounted upon said frame and having an outwardly projecting arm, a float carried by the outer end of said arm and adapted to rock said pulley first in one direction and then in the other, a jack shaft carried by the upper portion of said frame and having a pair of pulleys loosely mounted thereon, a cable passing over said pair of pulleys and around said first mentioned pulley and having downwardly extending free 90 ends, weights carried by said free ends for holding said cable taut, ratchet mechanism for connecting said pair of pulleys to said jack shaft for intermittently rotating said jack shaft in a predetermined direction, a sprocket wheel carried by said jack shaft, a power delivering shaft mounted adjacent 95 said jack shaft, an endless chain passing over said sprocket wheels and having a downwardly looped portion between such sprocket wheels, a roller fitted within the downwardly looped portion of said chain, and a heavy weight carried by said roller and urging said looped portion downwardly, and a flywheel 100 carried by said power delivering shaft.

105 In testimony that I claim the foregoing I have hereunto set my hand at Milwaukee, in the county of Milwaukee and State of Wisconsin.

OLIVER L. DARWIN.
